UNITED STATES PATENT OFFICE.

ETHELBERT M. FRASER, OF YONKERS, NEW YORK, ASSIGNOR, BY MESNE ASSIGNMENTS, TO GENERAL ELEVATOR COMPANY, OF JERSEY CITY, NEW JERSEY, A CORPORATION OF NEW JERSEY.

ELECTRIC ELEVATOR SYSTEM.

1,093,583.

Specification of Letters Patent. Patented Apr. 14, 1914.

Application filed July 29, 1912. Serial No. 711,957.

REISSUED

To all whom it may concern:

Be it known that I, ETHELBERT M. FRASER, a citizen of the Dominion of Canada, residing at Yonkers, county of Westchester, and 5 State of New York, have invented a new and useful Improvement in Electric Elevator Systems, of which the following is a specification.

In its broadest aspects, my improved electric elevator system or hoisting apparatus, which is of the traction type, comprises two independently-operated pulleys or driving members arranged to rotate about the same axis or parallel axes, an idler pulley or 15 sheave, and power-transmitting means.

In one embodiment of my invention, my improved electric elevator system comprises two shunt-wound electric motors, whose armature shafts are in alinement and coupled 20 rigidly together so as to revolve in unison and whose field structures are mounted so as to rotate independently of each other in opposite directions, each field structure carrying a pulley or sheave, an idler pulley or 25 sheave, and a flexible connector passing over and engaging said pulleys or sheaves, one end of the connector being connected to the car and the other end to a counterweight.

One of the objects of my invention is to 30 provide an electric elevator system, comprising two electric motors or dynamos whose armatures are mechanically connected together and having rotatable field magnets, in which the elevator car is controlled by 35 varying the field strength of either or both motors.

Another object is to provide an electric elevator system in which the power-operating instrumentalities will oppose each other, 40 thereby constituting an electric lock or brake to hold the car from descending or ascending.

Another object is to provide an electric traction elevator system or hoisting apparatus, comprising two electric motors or dynamos having rotatable field magnets and 45 armatures, in which the power-transmitting means is driven by two independently-operated pulleys or sheaves connected to the field structures rotating in opposite directions.

50 Another object is to provide an electric elevator system in which there are no sudden

rushes of current from or into the line when the car is started or stopped.

With the above and other objects in view, my invention consists of the construction, arrangements and combinations of parts hereinafter described and claimed.

An electric elevator or hoisting system embodying the features of my invention is illustrated in the accompanying drawings, 60 forming a part of this specification, in which—

Figure 1 is a view illustrating diagrammatically the arrangement of the independently-operated pulleys or sheaves, the idler pulley or sheave, and the power-transmitting means connected to the car and counterweight. Fig. 2 is a view partly in section of the operating motors, the idler pulley or sheave, and the power-transmitting means. 70 Fig. 3 is a wiring diagram.

In the drawings, similar figures of reference refer to similar parts throughout the several views.

As shown in Fig. 1, my improved electric 75 elevator or hoisting system comprises the two independently-operated pulleys or sheaves 10 and 11 preferably arranged to rotate about the same axis or shaft 12, the idler pulley or sheave 13, and the power-transmitting means 14. In the embodiment of my invention as shown, the power-transmitting means 14 are connected to the car 15, and the counterweight 16. Being merely diagrammatic, no bearings for the different rotating 80 elements are shown in Fig. 1, this feature being shown in detail in Fig. 2.

Referring to Fig. 2, the pulley or sheave 10 forms a part of or is secured to the field structure 17 of the motor 18, and the pulley 90 or sheave 11 forms a part of or is secured to the field structure 19 of the motor 20. The motors 18 and 20, which are of the standard shunt-wound type, comprise the field structures 17, 19, the armatures 21, 22, and the 95 commutators 26, 26, respectively. The armature shafts 12, 12 are preferably in alinement and rigidly secured together by the coupling 23, or, a unitary armature shaft may be used for the two motors. The armature shafts 12, 12 are suitably supported in bearings 24, 24 to permit of the shafts and ar-

matures 21, 22 revolving in unison. The field structures 17, 19, are also suitably supported in bearings 25, 25 to permit of the field structures rotating independently of each other 5 and of the armatures in either direction. If desired, a fly-wheel 27 may be mounted on the shaft of the armatures for the purpose of storing up and giving out power, thereby causing the flow of current from the main 10 source of supply to be more uniform and reducing the sudden rushes of current when starting or stopping the elevator. The idler pulley or sheave 13 is suitably supported in the hanger 28' and arranged so as to rotate 15 freely in either direction. The power-transmitting means preferably comprise a plurality of iron hoisting ropes 14 which engage grooves 28, 28 in the pulleys or sheaves 10, 11 and 13, the ropes being connected at one 20 end to the car 15 and at the other end to the counterweight 16. As will be shown hereinafter, it is not necessary to provide a friction brake to control the movement of the car, as the two motors under certain conditions 25 constitute an electric locking device to hold the car from ascending or descending. In case, however, there should be a cessation 30 in the current supply, means are provided for holding the field structures of the motors 35 from rotating thereby preventing the car from ascending or descending, or if preferred, means for gripping the hoisting ropes may be used.

As shown in Fig. 3, the field magnets of 35 the motors 18 and 20 are electrically connected up in series and connected across the line or power mains 30 and 31, while the armatures 21, 22 are in multiple and connected across the line. The system is also provided with the usual armature starting rheostat 34, a suitable fixed resistance 32 in the field circuits, and a plain field rheostat 33 to vary the field strength of either motor. In the embodiment of my invention 45 as illustrated the rheostat 33 is placed in the elevator car.

The method of operation is as follows: The armatures are started up and rotate clockwise as indicated by the arrows (Fig. 50 1) at say 500 revolutions per minute, while the field structures remain stationary. For the purpose of illustration, the field magnet is considered to be rotating in the plus direction when rotating opposite to its armature, and in the minus direction when it rotates in the same direction as its armature, the algebraic sum of the speeds of the armature and field magnet being the effective speed of the armature. If the field 55 magnet does not rotate, the speed of the armature will be the effective speed. If there is a load on the car, and the weight of the car and load is in excess of that of the counterweight, the natural tendency 60 would be for the car and load to descend,

but by so doing it would rotate the field structure 19 in the opposite direction to its armature 22, in which event motor 20 would act as a dynamo, and a current would be generated and sent into the line. At the 70 same time, the field structure 17 would be rotated in the same direction as its armature 21, the effect being to make this part of the apparatus act as a motor and take current from the line. The ultimate effect 75 of the armature 22 sending current into the line and the armature 21 taking current from the line is to prevent the field structures 17, 19, from rotating, thereby holding the car and load from descending. That 80 is, the arrangement of having both armatures connected to the line and the field magnets of the two motors of the same strength constitutes an electric locking device. 85

When it is desired to raise the car and load (it is assumed that the armatures are running at the maximum speed of 500 revolutions per minute when the car is at rest), field strength of motor 20 is strengthened 90 sufficiently, for example, to make the effective speed 400 revolutions per minute. As the armature shafts of the two motors are connected together, in order to permit armature 22 to slow up it would be necessary to lower the speed of armature 21. As the field structure strength of motor 18 has not been changed, armature 21 opposes the slowing up effect of armature 22. Armature 20 not being able to slow up and 95 field structure 19 being free to rotate, the latter will turn in the same direction as the armature or in a minus direction, the effect being the same as if the armature 20 were slowed up. 100

As the field structures 17, 19, are connected by the hoisting ropes 14, one cannot rotate without the other, and as field structure 19 rotates in the minus direction the field structure 17 will rotate at the same 110 speed in the plus direction. The field strength of motor 18 remaining the same and field structure 17 rotating in the plus direction, armature 21 will slow up the same number of revolutions as the field structure 115 17 turns in the plus direction. The final effect of strengthening the field magnets of motor 20 to get an effective armature speed of 400 revolutions per minute and keeping the field strength of motor 18 constant to 120 get an effective armature speed of 500 revolutions per minute is to cause the armatures 21, 22 to slow up to 450 revolutions per minute, the field structure 19 to rotate 50 revolutions per minute in the minus direction and the field structure 17 to rotate 50 revolutions per minute in the plus direction. 125

Whenever it is desired to stop the elevator car, the field strength of motor 20 is weakened to the original density or its field 130

strength is made the same as that of motor 18, thereby preventing the field structures from rotating and effectually locking or braking the car.

5 In order to lower the car, the field strength of motor 18 is increased and the field strength of motor 20 is maintained at the normal density, the action being the same as above outlined when the car is raised except that the direction of rotation of the field structures 17, 19, is reversed.

From the foregoing it will be seen that the armatures and fly-wheel are slowed up when the car is started in motion, and they 15 are speeded up when the car is stopped. This is a decidedly beneficial effect as the momentum of the armatures and fly-wheel is used to help start the car and counter-weight from a state of rest, and it is taken 20 up in increasing the speed of the armatures and fly-wheel. The ultimate effect is to prevent sudden rushes of current from or into the line when starting or stopping the car. These sudden rushes of current have been 25 one of the greatest defects of electric elevators, especially where a number of elevators have been operated *in banc* from an isolated plant.

As it is possible to operate the system with 30 armatures running at a constant speed, the normal speed will be the average speed, and as the field strength of one motor is weakened the field strength of the other motor is increased in exact proportion.

35 It will be obvious that numerous omissions, substitutions and changes may be made in the various parts, arrangements and wiring herein shown and described without, however, departing from my invention. 40 It is to be further understood that I do not wish to be limited to the specific features of construction and arrangement of parts, or to the specific application of my invention, herein set forth.

45 Having thus described my invention, what I claim as new and desire to secure by Letters Patent, is:

1. In an electric elevator system, the combination with two electric motors having rotatable armatures and field structures rotatable in opposite directions of a plurality of pulleys, two of said pulleys being secured to and driven by said field structures, and power-transmitting means engaging said 55 pulleys.

2. In an electric elevator system, the combination with two electric motors having their armatures mechanically coupled together and their field structures rotatable in opposite directions, of means for varying the field strength of either or both of said motors, and power-transmitting means driven by said field structures.

3. In an electric elevator system, the combination with a car, of a counterweight, two

electric motors having rotatable field structures and armatures, means for varying the field strength of said motors, a plurality of sheaves, two of said sheaves being operated by said field structures, and power-transmitting means connecting said car and counter-weight and engaging said sheaves. 70

4. The method of operating an electric elevator driven by two electric motors or dynamos, having their armature shafts mechanically connected together and their field magnets rotatable in opposite directions, which consists in making the field strength of the two motors or dynamos unequal so that one motor or dynamo will always act as 75 a motor when the other acts as a dynamo, and transmitting the reactive thrust of the armatures on the field magnets to an elevator car and counterweight.

5. The method of controlling an elevator 85 car driven by two electric motors or dynamos, having their armature shafts mechanically connected together and their field magnets rotatable in opposite directions, which consists in varying the field strength 90 of either or both of said motors or dynamos to control the direction of rotation of said field magnets.

6. In an electric elevator system, the combination with two electric motors having 95 their armatures mechanically coupled together and field structures rotatable in opposite directions, of means for varying the relative speeds and direction of rotation of said field structures, and a flexible connector 100 engaging said field structures.

7. In an electric elevator system, the combination with two electric motors having rotatable armatures and field magnets rotatable in opposite directions, of a sheave or 105 pulley connected to the field magnets of each motor and driven thereby, an independent idler sheave or pulley, and a flexible connector engaging all of said sheaves or pulleys. 110

8. In an electric elevator system, the combination with two electric motors having armatures mechanically coupled together and independently rotatable field structures, of a sheave or pulley driven by each of said 115 field structures, an independent idler sheave or pulley, a flexible connector engaging all of said sheaves or pulleys, and means for controlling the speed and direction of rotation of said field structures. 120

9. In an electric elevator system, the combination with two electric motors having armatures mechanically coupled together and independently rotatable field structures, of a sheave or pulley carried by each of said field structures and driven thereby, an independent idler sheave or pulley, a flexible connector engaging all of said sheaves or pulleys, and means for varying the field strength of either or both of said motors. 125 130

10. The combination with two electric motors having their armatures mechanically coupled together and their field structures rotatable in opposite directions at the same speed, of a pulley or sheave carried by each of said field structures, an independent idler sheave or pulley, a flexible connector engaging all of said pulleys or sheaves, and means for varying the speed and direction of rotation of said field structures.

11. The combination with the power mains or source of current supply, of two electric motors having rotatable field magnets electrically connected in series across the power mains, armatures electrically connected in multiple across the power mains and their armature shafts mechanically coupled together, a pulley or sheave carried by the field structure of each motor, an independent idler sheave or pulley, and power-transmitting means engaging all of said pulleys or sheaves and driven by the two first-mentioned pulleys or sheaves.

12. The combination with the power mains or source of current supply, of two electric motors having rotatable field magnets electrically connected in series across the power mains, armatures electrically connected in multiple across the power mains and their armature shafts mechanically coupled together, a pulley or sheave driven by the field magnets of each motor, an independent idler sheave or pulley, power-transmitting means engaging all of said pulleys or sheaves and driven by the

two first-mentioned pulleys or sheaves, and means for varying the speed and direction of rotation of said field magnets.

13. In an electric elevator system the combination with a car, of a counterweight, two electric motors having rotatable fields and armatures, said armatures being mechanically coupled together, means for varying the field strengths of said motors, a pulley driven by each of said fields, an idler pulley, and a flexible connector connected at one end to said car and passing over one of the pulleys driven by one of said fields to said idler pulley and thence in the opposite direction over the pulley driven by the other of said fields and connected at its other end to said counterweight.

14. The method of operating an electric elevator driven by two electric motors or dynamos, having their armature shafts mechanically connected together and their field magnets rotatable in opposite directions, which consists in transmitting the reactive thrust of the armatures on the field magnets to an elevator car and counterweight and making the field strength of the two motors equal to stop the car and varying the field strength of either or both of said motors to move the car up or down.

In testimony whereof, I sign this specification in the presence of two witnesses.

ETHELBERT M. FRASER.
